(57) **CLAIM**

The ornamental design for a food container, as shown and described.

DESCRIPTION

The present application refers to a new and original food container that consists of a house-hold instrument used to packaging food products.

The food container has a new, exclusive and modern design which provides the product an esthetic appeal.

FIG. 1 shows an upper perspective view of the food container, FIG. 2 shows a bottom perspective view of the food container, FIG. 3 shows an upper view of the food container, FIG. 4 shows a bottom view of the food container, FIG. 5 shows any side view of the food container; and, FIG. 6 shows a front view of the food container.

The FIGS. 1, 2, 3, 4, 5 and 6 show that the food container consists of a sweet pepper format.

Said food container (1) has an upper body (2) and a bottom body (3).

The food container (1) also has a hinge (4) connecting the bodies (2) and (3), and closing flanges (5).
